NONSKID ATTACHMENT FOR SHOES

Stephen L. Gingo, McKeesport, Pa.

Application January 8, 1941, Serial No. 373,663

2 Claims. (Cl. 36—62)

The present invention relates generally to a non-skid attachment for shoes or the like.

All non-skid attachments of the class in question, with which I am familiar, are highly objectionable for all practical purposes, for various reasons. The first and more important is the fact that by virtue of their size and cumbersome construction they cannot be worn with comfort, and greatly interfere with the proper and natural bending of the foot while walking. Equally objectionable is the fact that they not only cover the major portion of the sole of the shoe, and yet provide only a comparatively small degree of non-skid protection, but employ means for securing the attachment to the shoe which not only causes discomfort to the wearer, but also seriously mars the finish or surface of the shoe itself.

Therefore, the primary object of the instant invention resides in the provision of a non-skid attachment of the character mentioned, which eliminates all of the above noted objections, and provides one which is simpler in construction, more sturdy and compact, and capable of being manufactured and sold at a nominal cost.

One of the chief characteristics of the present invention resides in the provision of a non-skid attachment for shoes designed to afford maximum non-skid protection with a minimum of non-skid surface area, thus allowing freedom for the natural bending of the foot while walking.

In carrying out my invention, I also provide a novel means for firmly securing the attachment to the shoe in a manner which eliminates all discomfort to the wearer, protecting the surface of the shoe from being marred or injured, and at the same time permit the attachment to be quickly and conveniently secured to or removed from the shoe as the occasion might require.

Other objects and advantages of the invention will appear when the following detail description is read in connection with the accompanying drawings, the invention residing in the construction, combination and arrangement of parts as claimed.

In the drawings forming part of this application like numerals of reference indicate similar parts in the several views and wherein:

Figure 1 is a fragmentary plan view of a shoe showing by dotted lines the attachment associated therewith.

Figure 2 is a bottom plan view of Figure 1.

Figure 3 is a view of the attachment removed from the shoe.

Figure 4 is a front end elevation of the attachment showing it applied to a shoe.

Figure 5 is a view of a slightly modified form of the invention.

Before entering into a detail description of what is herein illustrated, I desire to have it understood that the present invention is capable of being used in various capacities, and may be employed to convert the ordinary shoes into hiking or golf shoes, while proper kinds of cleats may be employed to permit use of the invention for safe walking over oily pipes or surfaces, as encountered in the pipe industry. Consequently, it is to be understood that a general application of the invention is contemplated by the claims.

Referring to the drawings in detail, 10 and 11 indicate the respective sections of the attachment. Each of these sections carry a number of cleats 12 of any desired character, depending of course upon the particular use for which the attachment is to be employed. These cleats may be attached or secured to their respective sections in any suitable manner, although in accordance with the specific embodiment of the invention herein illustrated, the cleats 12 are stamped from the section and are preferably of the contour shown.

The sections 10 and 11 are relatively adjustable to vary the size of the attachment, so that the latter can readily accommodate itself to shoes of different size and style. While this adjustment may be accomplished in any suitable manner, I preferably provide the section 11 with a tongue 13 having spaced parallel slots 14. The tongue 13 reposes upon the section 10 and is adapted to be held fixed relatively thereto in any given position by suitable fastening elements 15 carried by the section 10 and received by the slots 14 of the section 11.

As hereinabove stated, one of the chief characteristics of the instant invention resides in the comparatively narrow elongated contour of the attachment as a whole, whereby maximum non-skid protection is obtained with a minimum of non-skid surface area. Manifestly, the attachment is adapted to extend across the sole of the shoe, and is designed to permit of its application thereto at preferably the angle as shown, not only for the purpose just mentioned, but also to allow for perfect freedom and natural bending of the foot while walking. Consequently, in order to attain these objects, the outer end of each section is slightly curved transversely as illustrated, while rising from each curved end is a shoe sole engaging clip. Each clip includes a vertical flange 16 and a right-angularly disposed inwardly extending flange 17. These clips may

be secured to the sole of the shoe in any suitable manner, but I preferably employ tightening screws 18 carried by the flanges 17. It will be noted that these tightening screws are arranged at suitable angles to permit of their use without allowing them to contact or mar the upper of the shoe. By virtue of this construction, the attachment may not only be more effectively secured to the shoe with a minimum of time and effort, but also eliminates the use of straps and other analogous fastening means which not only causes discomfort to the wearer, but frequently mars or damages the upper of the shoe. Furthermore, the present invention is designed to permit the attachment as a whole to be readily and conveniently associated with or removed from the shoe as the occasion may require.

In Figure 5 I have illustrated a slight modification of section 11. In this view the section is indicated at 11' and is provided with a relatively narrow tongue 13' having a single slot 14'. The section is provided with cleats 12' and a sole engaging clip including the vertical flange 16' and horizontally flange 17', the latter carrying the angularly disposed fastening screws 18'. This embodiment of the invention is the same as that hereinabove described, with the exception of the relatively narrow tongue having a single slot, which not only permits the section to be adjusted toward and away from its associated section, but also permits of slight pivotal movement of the section 11 in its adjustment to accommodate a shoe of any particular size or style.

While it is believed that from the foregoing description the nature and advantages of the invention will be readily apparent, I desire to have it understood that I do not limit myself to what is herein shown or described, and that such changes may be resorted to when desired as fall within the scope of what is claimed.

What is claimed is:

1. A non-skid attachment for shoes, comprising a comparatively narrow elongated device adapted to extend at an angle across the sole of the shoe to provide maximum non-skid protection with a minimum of non-skid surface area, said device including relatively adjustable overlapping sections, means for holding said sections fixed relatively in any given position, cleats carried by said sections, sole engaging clips rising from the outer ends of the sections, and sole engaging clamping screws mounted on the clips at an angle thereto.
- 10 2. A non-skid attachment for shoes, comprising a comparatively narrow elongated device adapted to extend at an oblique angle across the sole of the shoe, said device including relatively adjustable sections, each including parallel longitudinal edges, and a curved outer edge, sole engaging clips carried by the outer edges of the respective sections and wholly disposed between said parallel edges thereof, means for holding said sections fixed relatively, cleats carried by each section, and means for securing the device to the shoe.

STEPHEN L. GINGO.
